UNITED STATES PATENT OFFICE

RICHARD RUEMELIN, OF MILWAUKEE, WISCONSIN

DUST ARRESTER

Application filed June 24, 1929. Serial No. 373,155.

My invention relates to a dust arrester for vacuum and pressure systems to clean the dust from the air being adapted to be operable with sand blasting equipment and hoods where sand blasting is accomplished to take the air out of the sand blasting hood and directed to my dust arrester in a manner to clean the air of the dust and sand and to also be operable readily with vacuum type of dust arresters to collect the dust within my dust arresting hose bag means and dust arrester in a very efficient and desirable manner.

A feature of my invention resides in a dust arrester having a series of hose bag cleaners operable to provide a long continuous tubular bag-like dust arrester through which the air may escape, the tubular bag members collecting the dust within the same and having a long continuous formation extending up from the base of the dust arrester which collects the heavy dust in the bottom of the arrester which is continually shaken down from the hose bags which extend up in long continuous U-like members.

It is a feature of my dust arrester to provide a long tubular hose-like bag of cloth or textile material which is made from a strip of cloth folded and sewed to form a long tubular hose-like bag to provide a simple and economical dust arrester bag that can be readily made into the desired tubular formation of the desired size without necessarily being woven in a tubular formation but being made from the flat strip of cloth folded and sewed with a longitudinal seam.

It is also a feature of my invention to provide a dust arrester of a tubular U-shaped nature with means for supporting the central upper portion of the same by equalizing means which permits the end of the tubular arrester to depend equally from the equalizer on either side thereof. A further feature of the invention resides in means for operating the equalizing member to shake the dust arrester tube to cause the dust which may collect upon the walls of the same in the operation thereof to fall down to the open ends of the tubular collector and be deposited in a dust collector base. It is

also an important feature of my invention to provide a means of fastening the free ends of my dust arrester bag or tube to collars which are adapted to hold the ends of the dust arrester bag or hose members wide open and having a beaded annular edge over which the bags are adapted to slip to permit a strap-like band to extend about the collar below the beaded edge of the same and engage the tubular bag to securely fasten the same thereto to form a tight joint and yet to provide means to permit the ends of the bags to be easily disengaged from the spreading collars.

A feature of my dust arrester resides in means for supporting the upper end of the dust arresting bag by a triangular equalizing block means which connects with a spring rod for suspending the equalizing block and to take up the inequalities in the length of the bag in the dust arrester. This equalizing means may be also accomplished by a circular wheel-like member engaging the top or middle portion of the tubular dust arresting bag, together with the spring supporting rod. Suitable shaking means is provided for shaking the accumulated dust inside of the bag to deposit the dust in a collector below the ends of the same.

These features and others will be more fully and clearly hereinafter set forth in the specification and claims.

In the drawings forming a part of my invention:

Figure 1 illustrates a perspective view of my dust arrester with the series of dust arresting tubular or hose-like bags extending upward in the same.

Figure 2 illustrates a detail showing one means of supporting the hose-like bag dust arrester which forms one of the dust arresting bags in my dust arrester.

Figure 3 illustrates another method of supporting the hose-like dust arrester bag.

Figure 4 illustrates an enlarged detail in section showing the attachment of the free ends of the tubular dust arresting bag to show the attachment to the dust collecting base.

Figure 5 illustrates diagrammatically the sewing of the flat strips into a tubular formation to provide a tubular or hose-like dust arresting bag.

5 Figure 6 is a cross section through the bag in enlarged formation to show the relative sewing along the side with the longitudinal seam and body of the bag in transverse cross section.

10 My dust arrester A is formed with a suitable frame portion B which is adapted to provide a means of supporting a series of dust arresting tubular or hose-like bags C.

15 The dust arrester A is provided with a dust collecting base D which collects the dust within the base of the dust arrester A and receives the accumulated dust from the dust arrester bags C when the bags are shaken and the dust is caused to fall down out of the 20 open ends of the bags C. A suitable clean out opening 10 is provided in the dust collecting base. This base is preferably positioned below the open ends of the dust collector bags C.

25 An inlet tube 11 is provided for forcing the dusty air into my dust arrester A so as to direct the same up into and out of the cloth dust arrester bags C. Obviously the bags C may be operated to be used equally well with 30 a vacuum in cases where a vacuum cleaning system is desirable. The illustration however, shows the preferred operation with the pressure where the dusty air is introduced through the tubular member 11 and forced up 35 out of the bags C. The dust will collect on the inner sides of the bags C and by means which will be hereinafter described, the dust is shaken off into the compartment D in the lower portion of the dust arrester A.

40 The hose bags C are formed by tubular cloth bags 12 which are of a long continuous nature either formed by a tubular weaving of the material to form a hose-like cloth dust arrester bag formed in a simple and 45 economical manner. These bags may be formed by taking a piece of textile material which is flat and folding it so that it can be sewn with a longitudinal seam 13 extending along the side of the tubular bag 12, thereby 50 forming a tubular dust arrester bag in an economical manner.

55 My dust arrester A is adapted to be used where it is desirable to clean a large amount of dusty air so that the arrester can continue 60 to operate for a long period without particular attention or the cleaning of the parts or the bag or even the cleaning out of the dust arrester. To accomplish these features efficiently it is desirable to have long continuous dust collecting bags having a large area by their long continuous formation for the escape of the clean air and yet collecting all of the dust in an efficient and desirable manner. I accomplish this by the long tubular- 65 dust collector bags of a hose-like or tubular-

like formation such as C. These bags are adapted to be held with their ends 14 connector over the attaching collars 15 which are formed with an annular means 16 about the upper end of the same to form a shoulder 70 for holding the open ends 14 of the bags C attached to the collar and by means of a wide strap member 17 which is drawn tightly around the outer surface of the open ends 14 of the bags C, the bags are firmly and securely attached to the collars 15. The collars 15 are connected to the top 18 of the dust collector base so that any dust collected by the bags C will be easily passed out 75 through the collars 15 by reason of the collars 15 holding the ends of the bags C wide open. The attaching means, as just described, by the collars 15, the annular shoulder 16 and the strap 17 provide a means of attaching the open ends of the bag C in such a 80 manner as to permit the easy attachment and removal of the ends of the bag when it is desired.

85 My dust arrester is provided with an equalizing means in the form of the triangular block 20 which engages the bags C centrally between the ends thereof and the equalizer 20 is supported by the rod end 21 of the spring 22 which pivotally engages at 23 through the block 20 by the portion 24 of 90 the end of the rod 21. This pivotally supports the equalizer block 20 to hold the center portion of the bags C so that an equalizing supporting means is provided between the ends of the bag C. This equalizer supporting means included in the block 20 and the spring 22 provides a means of holding the mid portion of the bags C projecting up and down in the dust arrester A so that a 95 multiplicity of bags C may be used in a 100 small space to provide a large cleaning area by the tubular hose-like bags C in a very 105 small compact dust arrester such as is illustrated in my dust arrester A shown in Figure 1.

110 The spring 22 places a slight tension on the bags centrally between the ends by the equalizer 20 thereby holding the bags C stretched upward in the arrester A. The tension of the spring 22 is just sufficient to hold the center portions of the bags upward and in position in the arrester so that when the air pressure is off the bags, they will not drop down in the arrester but they will be held upward always in the right position and also 115 to place a slight tension on the same so as to hold the dust arrester bags C so that they may be operated by the shaker means to shake the dust which accumulates on the inside of the same in the operation of the dust arrester A.

120 The shaking of my dust arrester A is accomplished by the engagement of the rod 21 by the transversely extending members 25. These bars 25 engage across the upper end 125

5 of the dust arrester A as illustrated in Figure 1 and are connected at one end with shaker levers 26 which are adapted to be operated by the shaker rod 27 either by the hand lever 28 or by a suitable oscillating means which 10 may be power operated to continue to shake the bars 25 in a manner to continue the shaking operation during the operation of the dust arrester A. The power operating shaker means is not illustrated as this may be accomplished in any suitable manner by power operated means which vibrates or shakes the bars 25 back and forth, in a manner to shake the rod 21 and thereby shaking the upper 15 looped ends 12' of the bags C.

15 In Figure 3 I have illustrated a roller 29 which is pivoted to the portion 24 of the rod 21 of the spring 22 in a manner so as to provide a roller equalizer 29 for the upper looped 20 ends 12' of the bags C. This permits the upper or looped ends 12' of the bag to be equalized in relation to the depending portions extending downward from the looped 25 portion 12'.

25 My long tubular dust collector bags C provide a very efficient means of operating a dust arrester for sand blasting cabinets and which are particularly adapted to draw the dusty air out of the sand blasting cabinets and introduce it into my dust arrester A through the tubular introductory pipe 11 blowing the dusty air up into the bags C and these bags are adapted to accomplish the cleaning of the air in a very efficient manner being designed 30 to operate for a long period of continuous use so efficiently as to thoroughly clean the air and permit the air to pass out of the same virtually free of dust. Without the long tubular cleaners C this could not be accomplished. Thus, by means of the virtually U-shaped tubular cloth or textile cleaning bags C, together with the shaker means and the collector D, I provide a means of accomplishing the arresting of dust efficiently and in a 35 manner in which the dust arrester may be operated continuously for a long period of time and to clean a large volume of air with little or no attention for a long period of time.

40 Although I have described my collector tubes C as being formed in one piece and sewed at the seam 13 to form the tube, I desire to have it understood that other continuous flexible tubing, such as seamless tubing 45 could be used instead with the same degree of success.

45 The construction of the dust arrester A is such that it is economical to produce and the replacement of the dust collector tubes C 50 may be easily accomplished when it is desired.

55 In accordance with the patent statutes I have described the best embodiment of my invention and while the illustrations show a 60 particular detail, arrangement and forma-

tion of the parts, it is obvious that the same may be applied to other uses and carried out by other means within the scope of the following claims without departing from the spirit of the invention.

70 I claim:

1. A dust arrester including, a tubular bag member, means for supporting said bag in a manner to hold the ends thereof wide open, means for closing the bag intermediate the 75 ends and supporting the body of said bag projecting from the open ends under tension, and means for shaking the body portion adjacent the supporting means thereof.

2. A dust arrester bag including, a tubular body portion formed from a flat sheet of textile material folded and sewed with a longitudinal seam, means for securing the ends of said tubular bag to hold the same open, and means for supporting said bag, to 85 close the opening therethrough, centrally between the ends in position to be shaken to cause the dust arrested in said bag to be shaken out of both open ends thereof.

3. A dust arrester including, a base dust 90 collecting compartment, a series of connecting collars supported by said base compartment, a series of long tubular bags each connected to two of said connecting collars to hold the ends of said tubular bags open, and 95 means for supporting said bags with the opening therethrough closed midway between the ends under slight spring tension.

4. A dust arrester comprising, a base member adapted to form a dust collecting 100 compartment, a series of collars connected to the top of said base, a series of hose-like dust collecting bags secured to said collars, each bag extending in doubled formation and having its ends connected to a pair of 105 adjacent collars, means for supporting each bag midway between the ends to hold the same stretched fairly taut, equalizing means in said bag holding means, and shaker means adapted to shake said tubular bags to shake 110 the dust therefrom into said base compartment.

5. A dust arrester including, a multiplicity of long tubular textile dust arresting bags, means for supporting said bags in a 115 manner to be folded to close the passageway therethrough between their ends, and means for attaching the open ends of each of said bags to a common dust collector compartment.

6. A dust arrester including, a multiplicity of long dust collecting flexible tubular members, means for supporting said tubular members folded between their ends and adapted to depend to a common dust collecting compartment, and means for securing the ends of said tubular members to said dust collecting compartment.

7. A dust arrester including, a multiplicity of long tubular flexible dust collectors 130

- through which air may be passed, shaking members for supporting said tubular members midway between the ends thereof, a dust collecting compartment, and means for connecting each end of said tubular members to said dust collecting compartment, whereby dust collected in said tubular members is shaken down into said compartment.
8. A tubular dust arrester bag having, a body portion made of flexible textile material through which air may be passed, dust being adapted to collect on the surface of the bag, means for supporting the bag in U-shaped formation with the center part thereof closed and held spaced away from the ends thereof, and having an equalizing means for equalizing the ends of said bag in relation to each other, and means for connecting the open ends of said bag to a dust collector.
10. A tubular dust arrester bag having, a body portion made of flexible textile material through which air may be passed, dust being adapted to collect on the surface of the bag, means for supporting the bag in U-shaped formation with the center part thereof closed and held spaced away from the ends thereof, and having an equalizing means for equalizing the ends of said bag in relation to each other, and means for connecting the open ends of said bag to a dust collector.
15. A tubular dust arrester bag having, a body portion made of flexible textile material through which air may be passed, dust being adapted to collect on the surface of the bag, means for supporting the bag in U-shaped formation with the center part thereof closed and held spaced away from the ends thereof, and having an equalizing means for equalizing the ends of said bag in relation to each other, and means for connecting the open ends of said bag to a dust collector.
20. A hose-like dust bag for dust arresters, means for connecting the ends of said bag to a dust receiver, equalizing means for holding the mid-portion of said hose bag including spring means for holding the same taut, and shaker means for shaking the mid-portion of said hose bag to shake the dust therefrom into the dust collector.
25. A hose-like dust bag for dust arresters, means for connecting the ends of said bag to a dust receiver, equalizing means for holding the mid-portion of said hose bag including spring means for holding the same taut, and shaker means for shaking the mid-portion of said hose bag to shake the dust therefrom into the dust collector.
30. A tubular dust bag for dust arresters, means for holding both the ends of said bag to receive dusty air into said bag, means for supporting the mid-portion of said bag away from the ends, and means for shaking the mid-portion to shake the dust from said bag.
35. A dust arrester bag having a long hose-like tubular formation, means for supporting said bag in a doubled formation, the supporting means engaging the bag midway of the ends thereof, said supporting means including an equalizer and also means for holding the bag taut in doubled formation.
40. A dust arrester bag having a long hose-like tubular formation, means for supporting said bag in a doubled formation, the supporting means engaging the bag midway of the ends thereof, said supporting means including an equalizer and also means for holding the bag taut in doubled formation.

RICHARD RUEMELIN.
